PLANING BOTTOM FOR BOATS

Peter Rowland Crewe, Shanklin, Isle of Wight,
England, assignor to Saunders-Roe Limited,
Osborne, East Cowes, Isle of Wight, England

Application January 24, 1951, Serial No. 207,546
In Great Britain January 26, 1950

4 Claims. (Cl. 114—66.5)

1

This invention has for its principal object to provide a flying boat or other marine aircraft having a hull of streamline form in place of the normal planing bottom hull.

The invention provides a hull for a marine aircraft, which is generally of streamline form and having fitted to its undersurface, at a location near to the centre of gravity, a flap which is movable, about a transverse axis, between a retracted position in which it lies flush with the undersurface of the hull and a projected position, in which its forward end is accommodated in a recess in the hull and its rearward end projects beneath the hull to constitute a step. In flight, the flap will be retracted and the hull, being of streamline form, will have an air drag comparable with that of the fuselage of a convenient land plane.

The flap may be movable from retracted to projected position, and vice versa, by any convenient mechanism, e. g. by means of a hydraulic or electrical power unit. The pivotal axis of the flap is preferably so placed that the resultant water load on the flap during movement thereof acts thereon at a location close to the pivotal axis.

The flap, when projected, constitutes a step which fulfils a similar function to the main step on the planing bottom of an orthodox flying boat. The front wall of the cavity in the hull into which the front end of the flap lifts, when the flap is moved to projected position, forms a shelf which reflects and, to some extent at least, transforms into useful energy the spray thrown forward from the step, thus reducing the water drag on the hull during take-off. Ducts are provided in the cavity into which the front end of the plate rises for ejecting laterally the spray thrown back from the shelf.

I prefer to depart from a strictly streamline form of the hull by providing the same, rearwardly of the step, with a dropped afterbody, the undersurface of which extends parallel to the centre line of the hull. When the hull is provided with such a dropped afterbody, it may safely be landed with the flap retracted, if desired. Moreover, when the flying boat is travelling on the water with the flap projected, the dropped afterbody fulfils the same function as the afterbody of an orthodox flying boat, i. e. it keeps the trim and drag within reasonable limits at hump speeds and mid-planing speeds, it keeps the tail free from water, and gives good longitudinal stability at all speeds above the hump speed (i. e. the speed at which the trim and drag are at a maximum). The dropped afterbody also

2

avoids trouble due to suction of water such as would be encountered on the undersurface of the rear part of a hull shaped like a conventional fuselage, i. e. tapering upwardly from the flap to the stern.

Two alternative embodiments of the invention will now be described in detail, by way of example, with reference to the accompanying diagrammatic drawings, in which:

10 Fig. 1 is a side elevation of a flying boat according to the invention in flight,

Fig. 2 is a similar view showing the boat about to alight on the water,

15 Figs. 3 and 4 are respectively sections on the lines III—III and IV—IV in Fig. 1,

Fig. 5 is a side elevation of the flap on a larger scale,

Fig. 6 is a section on the line VI—VI in Fig. 5,

Fig. 7 is a side elevation of the bow plate,

20 Fig. 8 is a corresponding plan view, and

Fig. 9 is a side elevation of an alternative embodiment of flying boat.

The drawings, being diagrammatic, show the hull only of the flying boat, the wings and tail planes being omitted.

Considering first of all Figs. 1—8, it will be seen that the hull 10 of the flying boat is of generally streamline shape, and has no step. The afterbody of the hull is however dropped, its undersurface 11 extending parallel to the centre line of the hull.

30 Within a recess 12 (Fig. 5) in the hull is fitted a flap 13 which is rotatable about a transverse pivot 14 from the retracted position, shown in full lines, and the projected position shown in chain-dotted lines. The pivotal axis 14 of the flap 13 is at its upper surface and approximately midway in the length of the flap, and the resultant water load on the flap during movement thereof acts at a location close to the pivotal axis.

35 As will be seen, when the flap 13 is retracted, its undersurface is flush with the undersurface of the hull 10. When projected, however, the flap 13 constitutes a step which fulfils a similar function to the main step of an orthodox flying boat hull.

40 The flap is located with its centre below or somewhat forward of the centre of gravity of the aircraft. The front wall 15 (Fig. 5) of the cavity 12 in the hull constitutes, when the flap is in projected position, a shelf which reflects rearwardly part of the spray thrown forward from the step. Ducts 16 are provided in the walls of the hull and these ducts serve to eject laterally the spray thrown back from the shelf 15.

45 As will be clear from Fig. 5, the flap 13 is connected at its rear end to a fixed portion 17 of

the hull by a pair of toggle linkages 18 operable by a screw jack 19. The jack 19 may be operated by an electric motor (not shown) remotely controlled from the pilot's cockpit to straighten the toggle linkages 18 and project the flap and to collapse the toggle linkages 18 and retract the flap.

The hull 10 is fitted at each side with a bow chine strip 20 and a stern chine strip 21. These serve the same purpose as the chines of an orthodox flying boat, i. e. they prevent water from running up the sides and over the top of the hull and deflect spray during planing, so giving extra dynamic water lift. The aft chine strips 21 are near the bottom of the dropped afterbody 11, and assist the afterbody to act, as above described, in the same fashion as that of a conventional flying boat when the flap is projected. The dropped chine strips 21 also reduce water drag by preventing water from clinging to the side of the portion of the afterbody above them.

The hull is fitted with a bow plate 23 which can be retracted, for flight, into a recess 24 (Fig. 7) in the hull, so that, as shown in Fig. 1, its undersurface is flush with the undersurface of the hull, or projected, for take-off or landing, to the position shown in Figs. 2 and 7. It is then at a coarse angle of incidence so that it will give high water lift at low speeds. The purpose of the plate 23 is to lift the nose of the aircraft clear of the water at low speeds, and prevent it digging in at high speeds, thus preventing bow diving or the throwing of water over the pilot's coupe. At high planing speeds the plate 23 is normally well clear of the water.

The plate 23 is supported, at each side, as shown in Figs. 7 and 8, by a pair of links 25, 26, mounted respectively on transverse shafts 27 and 28 and joined by a pair of top links 29. A screw jack 30 is coupled to a pair of cranks 31 fixed to the shaft 27 and serves to rotate the shaft 27 and thereby to move the plate 23 from the projected to the retracted position and vice versa. An electric motor (not shown) remotely operable from the pilot's cockpit, is provided for actuating the jack 30.

Reference has so far been made to but a single flap. If desired, however, the hull may, as shown in Fig. 9, be provided with a number of flaps 113 of the above-described type set in line longitudinally and spaced symmetrically, or substantially so, in relation to the centre of gravity, the flaps being movable independently from retracted to projected position, and vice versa, by separate controls. Each of the flaps 113 is precisely similar to the flap 13 shown in Figs. 1-8 and is operated in similar fashion to move it from retracted to projected position.

What I claim as my invention and desire to secure by Letters Patent is:

1. A marine aircraft, having a stepless hull of substantially streamline form conforming generally in shape to the fuselage of an aircraft adapted to alight on land, and comprising a flap accommodated in a cavity in the base of said hull near the centre of gravity of the aircraft, said flap being pivoted to the hull for movement about a transverse axis spaced rearwardly from the leading edge of the flap, means for moving said flap about said transverse axis from a retracted position, in which its undersurface is flush with the undersurface of the hull, to a projected position in which the forward end of the flap is accommodated in the cavity and the rear end of the flap projects beneath the hull, a wall at the

front end of the cavity which serves to reflect backwardly spray thrown forward by the flap, when projected, and ducts in the hull for ejecting laterally from the cavity spray reflected by said wall.

10 2. A marine aircraft, having a stepless hull of substantially streamline form conforming generally in shape to the fuselage of an aircraft adapted to alight on land, the undersurface of the stern portion of said hull being substantially level with the undersurface of the centre portion thereof, and comprising a flap accommodated in a cavity in the base of said hull near the centre of gravity of the aircraft, said flap being pivoted to the hull for movement about a transverse axis spaced rearwardly from the leading edge of the flap, means for moving said flap about said transverse axis from a retracted position, in which its undersurface is flush with the undersurface of the hull, to a projected position in which the forward end of the flap is accommodated in the cavity and the rear end of the flap projects beneath the hull, a wall at the front end of the cavity which serves to reflect backwardly spray thrown forward by the flap, when projected, and ducts in the hull for ejecting laterally from the cavity spray reflected by said wall.

20 3. A marine aircraft, having a stepless hull of substantially streamline form conforming generally in shape to the fuselage of an aircraft adapted to alight on land, and comprising a flap accommodated in a cavity in the base of said hull near the centre of gravity of the aircraft, said flap being pivoted to the hull for movement about a transverse axis spaced rearwardly from the leading edge of the flap, means for moving said flap about said transverse axis from a retracted position, in which its undersurface is flush with the undersurface of the hull, to a projected position in which the forward end of the flap is accommodated in the cavity and the rear end of the flap projects beneath the hull, a wall at the front end of the cavity which serves to reflect backwardly spray thrown forward by the flap, when projected, and ducts in the hull for ejecting laterally from the cavity spray reflected by said wall, a plate located beneath the extreme bow portion only of said hull, said plate being normally housed in a recess in said hull, and means for projecting said plate to a position beneath the hull in which said plate is at a coarse angle of incidence to the water.

4. A marine aircraft, having a stepless hull of substantially streamline form conforming generally in shape to the fuselage of an aircraft adapted to alight on land, and comprising a plurality of flaps arranged in line in the fore and aft direction and disposed substantially symmetrically with regard to the centre of gravity of the aircraft, each of said flaps being accommodated in a cavity in the base of said hull near the centre of gravity of the aircraft, said flaps being pivoted to the hull for movement about a transverse axis spaced rearwardly from the leading edge of the flap, means for moving each of said flaps about its pivotal axis from a retracted position in which its undersurface is flush with the undersurface of the hull, to a projected position in which the forward end of the flap is accommodated in the cavity and the rear end of the flap projects beneath the hull, walls at the front ends of said cavities for reflecting backwardly spray thrown forward by the flaps, when projected, and ducts in the hull for ejecting laterally

from each cavity spray reflected by the front wall of the cavity.
